UNITED STATES PATENT OFFICE.

EASON L. SLOCUM, OF PAWTUCKET, RHODE ISLAND.

SECONDARY ELECTRIC CLOCK.

SPECIFICATION forming part of Letters Patent No. 416,148, dated November 26, 1889.

Application filed October 26, 1888. Serial No. 289,246. (No model.)

To all whom it may concern:

Be it known that I, EASON L. SLOCUM, a citizen of the United States, residing at Pawtucket, in the county of Providence and State 5 of Rhode Island, have invented certain new and useful Improvements in Secondary Electric Clocks, of which the following is a specification.

The object of my improvement is to provide an electric chronometer having a device constructed for driving and locking a cheap and simple mechanism, which can be run, if necessary, by a single battery-cell, insuring an absolutely correct action with a comparatively weak current of electricity, and I accomplish this by the means illustrated in the accompanying drawings, in which—

Figure 1 is a front elevation; Fig. 2, a side elevation; Fig. 3, a rear elevation; Fig. 4, a 20 side elevation on the side opposite to that shown in Fig. 2; Fig. 5, the armature, and Fig. 6 the slotted pawl.

Similar letters refer to similar parts throughout.

25 In the drawings, A designates the frame which forms the bearing for the arbor a, which carries the minute-hand of a secondary electric clock. On this arbor is mounted a wheel b, having one hundred and twenty teeth, so that whenever the wheel is moved forward two teeth the hand marks a minute on the dial. This pinioned wheel connects with a system of gears and pinions which move the hand marking the hour on the dial.

30 C designates the armature, which is a thin strip of metal bearing loosely on a V-shaped bearing. (See Fig. 5.) This bearing is made V-shaped in order that the armature to which the driving and locking mechanism is secured 35 may rest upon the said bearing at the smallest possible point of the V, which is of hardened steel, thus reducing the friction to a minimum and allowing the attraction of said armature to the magnet by an extremely light current of electricity, and also insuring freedom of action from any corrosion of said bearing.

D designates a coiled-wire spring secured into the post d, Figs. 1 and 3, which, with the post d' supports the cross-frame E, in 40 which is the rear bearing of the arbor a. The other end of this spring is secured in an aux-

iliary arm of the escapement, as will herein-after more specifically be shown.

The driving and locking mechanism is constructed with two arms g and h. On the arm 55 g is mounted a propelling-pawl c. This pawl is a thin strip of spring-steel, slightly bent to enable its end to engage with the gear-wheel, and is slotted where secured to the arm to enable it to be adjusted to a proper length 60 to engage the spur-wheel by the set-screw which secures it to said arm. This adjustable propelling-pawl is one of the features of my invention and employed in no other electric clock. On the arm h of the escapement 65 is formed an auxiliary arm h', having a right-angled lip h², upon which is adjusted the propelling-pawl c', slotted in the same manner and similar to the pawl c. These pawls are so adjusted (see Fig. 3) as to engage with the 70 teeth of the wheel b at points on the circumference of said wheel opposite to one another.

At the end of arm h of the driving mechanism is the lip h', and on the arm g, at the point on the circumference of the wheel directly opposite, is the lip k, which as the escapement oscillates engage with the teeth of the wheel b alternately with one another and, locking with said teeth, prevent the wheel 75 from moving forward until released. 80

When the armature C is attracted by the electro-magnet F, the armature takes the position indicated by the dotted lines in the drawings, (see Fig. 3) and the arms of the driving mechanism, secured, as described, to 85 said armature, move with the same and take the position indicated by the dotted lines. As the armature is attracted toward the magnet, the pawl c' presses against the teeth of the wheel b and pushes the wheel forward 90 one tooth. Immediately the lock k' engages with the wheel and firmly locks the same. The lip h² in its forward movement carries with itself the end of the wire spring D and the wire takes the position indicated by the 95 dotted lines. (See Fig. 3.) When the electro-magnet is devitalized, the force of the coiled-wire spring causes the arm of the driving mechanism to move back to its original position, and, moving back, causes the pawl c 100 to press the wheel b forward another tooth, the spring-pawl c' springing into the space

between the teeth of said wheel immediately in the rear of that before engaged by it, and the lock *k* immediately engages with the wheel and locks the same. The oscillation of the 5 arms of the driving mechanism alternately pushing and locking the geared wheel *b* the number of pinions (viz., one hundred and twenty) employed, move the minute-hand through a half-minute space on the dial by 10 each attraction of the armature. On account of the shortness of this space the movement of the propelling-pawls and the action of the locks are of necessity very positive. This 15 positive action of the pawls and locks forms an important feature of my invention, since it will prevent any possible fluctuations of the hands on the dial, which has been one of the serious objections in electric dials.

On the bridge *x*, secured to the frame, is 20 mounted a rest *y*, adjustable by means of a screw. This rest serves as a stop for the armature and prevents the springing of the right arm of the driving mechanism from a too forcible blow.

25 In Fig. 2, *O* designates a lever pivoted at *o* to the bridge *x*. To the aperture *o'* in the end of this lever may be attached a chain extending to the outside of the clock-case, the function of the lever being to operate the 30 mechanism of the clock and set the hands of the same by pressing the end of the lever forward against the propelling-anchor mechanism, as shown in the dotted line designated as *o*² in Fig. 3.

35 I am aware that previous to this application secondary electric clocks have been constructed, as by patents issued to William F. Weisberger, No. 314,634, and to Charles E. Barschig, No. 304,595, also to several others, 40 but constructed on an entirely different principle from mine. In their inventions the motion of the lever, after the devitalization of the electro-magnet, is secured by the use of a weight, or under the "gravity system," so 45 called, which is open to many serious objections.

50 In my construction both the armature and the arms of the driving mechanism are made very light, and an ounce spring will serve to move the mechanism, which permits the use of a very light current of electricity, and I calculate to be able to run my mechanism by the employment of a single-cell battery. Under the gravity system, however, a heavy 55 weight is employed, which, when the current is cut off, drops and carries with it the arm of the lever and the propelling-pawl. The action is so strong that the pawl must be locked into the pinions to prevent displacement, and 60 the distance of propulsion is so great that the hands fluctuate on the dial. Again, when a weight is used the clock must be mounted in just such a position, and the slightest variation in this position will cause serious displacement and fluctuations of the hands.

Experience has demonstrated that owing to the force necessarily employed to move the weight the propelling-pawl will occasionally jump two or more teeth. In my construction, however, as has been before described, 70 the armature is loosely mounted upon an anti-friction V-shaped bearing, and owing to the use of a fixed spring, secured as described, and the escapement, secured as described, the clock will run in any position in 75 which it may be placed, and the mechanism cannot be displaced by any jar, insuring absolutely correct movement of the hands under any circumstances. This is a point of great importance, since many secondary electric clocks are employed in mills, where it is necessary to have each clock run exactly like the main clock, and where, owing to the use of heavy machinery, a great amount of jar is 80 communicated to the walls.

85 My clock, like a watch, can be run in any position or under any circumstances.

What I claim as new, and desire to secure by Letters Patent, is—

1. The combination, substantially as hereinbefore described, of the electro-magnet, the armature, the driving and locking mechanism secured to said armature, the V-shaped anti-friction bearing, the arms *g* and *h* of the driving mechanism, the slotted adjustable pawl *c'*, mounted on the lip *h*² of the arm of the driving mechanism, the slotted adjustable pawl *c*, mounted on the arm *g* of the said driving mechanism, and the locks or stop-pawls *k'* *k*, mounted on opposite arms of the 95 escapement, engaging and locking the geared wheel.

2. The combination, substantially as hereinbefore described, of the electro-magnet, the armature, the driving and locking mechanism, and the coiled-wire spring *D*, secured to the post *d* and the lip *h*², for the purpose described.

3. The combination, substantially as hereinbefore described, of the electro-magnet, the armature, the arm extending from said armature and secured to the driving and locking mechanism, the arms *g* and *h* of said escapement, the lip *h*² of arm *h*, the slotted and adjustable pawls *c'* and *c*, mounted on the arms 110 *g* and *h* of said driving and locking mechanism and adjustable to said arms, as described, the locks *k'* and *k*, mounted opposite to one another on the arms *g* and *h*, respectively, alternately engaging with and locking the 115 geared wheel, the geared wheel *b*, and the wire spring *D*, secured to the shaft *d* and the lip *h*².

EASON L. SLOCUM.
